UNITED STATES PATENT OFFICE.

EDGAR W. POHLIG, OF NEW YORK, N. Y.

COMBINED DOOR LOCK AND STAY.

Application filed December 6, 1923. Serial No. 678,794.

To all whom it may concern:

Be it known that I, EDGAR W. POHLIG, a citizen of the United States, residing at New York city, borough of the Bronx, in the county of Bronx and State of New York, have invented certain new and useful Improvements in Combined Door Locks and Stays, of which the following is a specification.

10 This invention relates to builders' hardware and has particular reference to locks for doors, windows, or other relatively movable parts of structures. By the term "door," therefore, as used hereinafter, I 15 mean to cover broadly any such movable structure.

Among the objects of the invention is to provide a door lock including a bolt having both sliding and swinging movements with 20 respect to the part with which it is carried or is permanently connected and adapted for hooked interlocked co-operation with another fixed part of the lock and around which the bolt will swing as a pivot when 25 the door is to be opened only partially.

Another object is to provide in a most simple, reliable, and efficient manner a jimmmy-proof lock including a bolt carried by the door and having an outer free end adapted to overlap a fixed jamb member when the door swings shut and so constructed as to hook around said member when the bolt is slid toward the door for locking.

A still further object is to provide a rigid stay, designed to take the place of a commonly used chain on the inside of a door for the purpose of permitting a partial opening inward of the door in order to note who the caller may be or what his business is without intentionally opening the door far enough for him to enter or intrude. I have discovered, however, that a chain stay as commonly used is objectionable for various reasons including the fact that it is easily broken due to the fact that the intruder may, by seizing the door knob and giving the door a slam inward, readily snap the chain. In this improvement, however, I provide in place of the chain a rigid stay 45 which has positive engagement with a member carried by the door at any one of a number of different positions or degrees of opening of the door, and so the stay prevents such swinging of the door as just described

as would enable the intruder to break a chain.

With the foregoing and other objects in view the invention consists in the arrangement and combination of parts hereinafter described and claimed, and while the invention is not restricted to the exact details of construction disclosed or suggested herein, still for the purpose of illustrating a practical embodiment thereof reference is had to the accompanying drawings, in which like reference characters designate the same parts in the several views, and in which—

Figure 1 is a front elevation of a combined lock and stay corresponding to the arrangement of Fig. 2 on a small scale. 70

Fig. 2 is a plan view of the same on a larger scale and with parts in section on about the line 2—2 of Fig. 1.

Fig. 3 is a side elevation somewhat similar to Fig. 1 but with parts broken away just back of the front plate of the casing. 75

Fig. 3^a is a detail view of the central portion of Fig. 3 with parts in changed position.

Fig. 4 is a vertical transverse section on the broken line 4—4 of Fig. 3. 80

Fig. 5 is a plan view with parts in section through a modification, this figure indicating the relation of the stay to a partially open door. 85

Fig. 6 is a side elevation of the structure of Fig. 5.

Fig. 7 is a perspective view of a modified form of lock.

Fig. 8 is a horizontal section on the line 8—8 of Fig. 7. 90

Fig. 9 is a view indicating the application of my improvement to a common form of outside lock casing.

Fig. 10 is a detail view indicating the adaptability of the bolt for either a right or left hand door. 95

Referring now more specifically to the drawings, I show my improvement as comprising a combined bolt and stay 10 which may be of any suitable shape but shown as practically straight and made of flat bar metal but having formed on its outer or free end a hook 11, the point of which is toward the outside of the door in a vertical plane 100 and is movable toward or from the door for locking or unlocking the bolt in connection with a strong pin 12 carried by a rigid jamb

piece 13 anchored upon the corner of the jamb adjacent to the striking edge of the door when shut. The specific design of the jamb piece and the manner of applying it to the jamb may vary to a great extent without affecting the spirit of the invention. It is shown, however, as including a pair of horizontal wings 14 between the points of which the pin 12 extends and which wings are spaced sufficiently to admit the hook 11.

15 indicates a casing or frame of any suitable design or construction and connected rigidly by any suitable means to the door on the inside and adjacent to the striking edge. As shown in Figs. 2, 3, and 4, this casing is designed to accommodate certain internal movable members including a carrier 16 in the nature of a block of metal or its equivalent substantially rectangular 20 in form or in the nature of a short bolt and adapted for limited horizontal sliding movement, say to the extent of three-fourths of an inch in an ordinary construction, or from the position of Fig. 3 to that of Fig. 3^a. 25 This carrier is guided in a channel 17 and is recessed on its outer side to accommodate a dog or trip member 18 pivoted at 19, this dog being in the nature of a lever of the first class. One end or tail piece 18^a of the 30 dog registers with a notch 20 formed in the upper edge of the carrier, and by virtue of a spring 21 fixed at its outer end to the forward end of the carrier the tail piece 18^a is normally held elevated or opposite said notch while the other end or tooth 18^b of the dog is held depressed so as to occupy one or the other of a plurality of notches 22 formed in the bottom wall of the channel 17.

40 Any suitable means may be provided to manipulate the carrier for sliding it outward toward the striking edge of the door or inward toward the opposite direction. To this end I show two means. 23 is a 45 knob lever fixed in any suitable manner to the spindle 24 upon which an inside knob 25 is fixed. An elliptical cam 26 is fixed also upon the spindle 24 between the lever 23 and the adjacent side wall of the casing. 50 A spring 27 fixed at one end to the casing and bearing at its other end upon the cam tends to hold the cam and lever 23 in either of the positions shown in Figs. 3 and 3^a. The position of the carrier in Fig. 3 being 55 that when the door is locked, for unlocking the door the operator on the inside of the door grasps the knob and gives it a half turn to the left causing the lever 23 to move as shown by the arrow, when the shorter 60 end thereof will enter the notch 20, then depress the tail piece 18^a of the dog, lifting the tooth 18^b thereof out of the notch 22, and finally by wiping against the remote beveled side of the notch will move the carrier bodily to the position of Fig. 3^a. The 65

lever will be stopped in this partial rotation by the point or longer end 23' thereof striking against a suitable stop as at 28. By this time the tooth 18^b will have snapped into the next notch 22 whereby the carrier 70 will be locked in its outer or forward position.

A lug 29 projects downward from the lower edge of the carrier through a slot 30 in the wall aforesaid having the notches 22 and into a notch 31 formed in the upper edge of the bolt 10. Hence when the bolt is in the position shown in Figs. 1 to 3, the movement of the carrier will cause positively the sliding movement of bolt forward or rearward. In the main figures the parts are shown locked with the hooked end of the bolt in interlocking position with respect to the jamb piece, a condition or position which renders it impossible for the 80 door to be jimmied or for a tool to be introduced between the jamb and the striking edge of the door for spreading these parts.

The bolt normally rests upon or is slideable lengthwise in a seat 32 formed in the bottom portion of the casing, and it is retained therein as shown by two means,—a retainer 33 comprising two curved arms 33' extending inward from the main portion of the bottom of the casing and thence forward beyond the pin. These arms are connected by means of a vertical bar. Between the arms the bolt has ample room to slide as already described, and between the vertical bar and the main casing the bolt is free for swinging inward away from the door and around the axis of the pin 12 when the hook is in interlocking or locked position. When this bolt so swings inward from the door the lug 29 simply passes out of the notch 31 laterally. Under normal conditions the bolt is held from this inward swinging movement by means of a latch 34 slideable vertically with respect to a guide way 35 and a keeper 36.

Along the lower edge of the bolt are formed a series of notches 37 which may be spaced at various places along the bolt and into any one of which the lower arm 33' is adapted to be received when the bolt is swung inward from the door and it is desired to use it as a stay for holding the door ajar at any desired degree of opening. This action of the bolt may be further described as follows: The door being closed or locked as shown in Fig. 2, if it be desired to open the door only partially to interview a caller, the operator simply lifts the latch 34 and swings the bolt inward toward the position shown in Fig. 5 or approximately at right angles to the plane of the door, the lower edge of the bolt resting upon the lower arm 33' of the retainer. The door then may be opened and when the first notch 37 is 130

reached the bolt will drop and be positively engaged by the retainer holding the door at such position, giving a few inches of open space. If more space is desired as for the admission of a package, the operator on the inside will lift the inner end of the bolt and allow the door to open to the next or any succeeding notch 37. A stop member 38 is adjustable along the bolt to any desired position and is locked thereto by a set screw 39 or its equivalent which may be projected through any one of a series of holes or notches 40 formed in the bolt. By this means it is impossible for the caller to intrude by pushing or forcing his way through the door because the stop 38 will co-operate with the retainer 33 and positively limit the opening movement of the door according to the effective length of the bolt determined by the adjustment of the stop. For ordinary use of the door the bolt will be locked in position as shown in Fig. 3^a so that the door may swing open or shut freely so far as the locking bolt or stay 10 is concerned.

I also show in Figs. 2 and 3 a key lever 41 associated with any suitable conventional key mechanism 42 for manipulation of the lock carrier from the outside of the door. This lever 41 under the manual manipulation by key will be swung in the same direction as described above in connection with the bar 23, and its free end will enter the notch 20 and act upon the dog as then described but it may swing through a full circle instead of a partial circle. The carrier is wide enough as shown in Figs. 2 and 4 to be operated upon by either of these mechanisms.

In Figs. 5 and 6 I show a variation and simplification of my improvement but in which the bolt 10 and retainer 33 are practically the same as already described in detail. Instead of the notches 22 for cooperation with the tooth of the dog in the lock casing 15 I provide in this form a plurality of notches 22' formed in the top edge of the bolt and into either of which a lug 18' carried by the back of the latch 34' is adapted to engage for locking the bolt in either its forward or inward position according to whether the bolt shall or shall not be free with respect to the pin 12. The jamb piece 13 is or may be just the same as already described. Instead of the casing 15 I provide a plate or bracket 15' secured on the inside of the door and carrying the same retainer 33 as is described in connection with the casing. The lower edge of the bolt is provided with notches 37 and I employ an adjustable stop 38 as above described.

When the latch 34' is lifted slightly the bolt may be shifted longitudinally for hooking or unhooking it around the pin 12 and when the latch is dropped again it will hold the bolt in whichever position it is placed. The lower end of the latch will remain in

engagement with the front face of the bolt holding it in its flat position against the plate and limiting it for sliding movement only. For use of the bolt as a rigid stay as shown in Figs. 5 and 6, the latch 34' will be lifted far enough to clear the bolt and allow it to be swung away from the door as previously described.

In Figs. 7 and 8 the bolt 10', while having a hook 11 similar to the bolts already described for co-operation with the same type of jamb piece 13 or its equivalent, is retained for sliding co-operation only with a plate or bracket 15' fixed to the door. The bolt is shown retained by keepers 33^a and 36^a formed rigidly or integrally with the plate. A finger piece 43 is connected to the bolt and co-operating with the keeper 33^a constitutes a limiting stop for forward movement of the bolt and also serves as a means for moving the bolt inward into interlocking position with respect to the pin 12. At this time a gravity dog 18' pivoted at 19' will drop so that its tooth 44 will drop into a notch 22^a having at least one square shoulder for a positive locking means between the plate and the bolt when the bolt is in locking position. A finger piece 45 facilitates the lifting of this dog out of locking position when the bolt is to be moved forward as in the position of Fig. 7.

In Fig. 9 I show an outside lock casing 15^b which may be understood as being of any suitable or conventional design with respect to the usual locking catch or bolt but arranged to carry within it a locking bolt 10^b, having the hook 11 for cooperation with the standard jamb piece.

As indicated in Figs. 6 and 10 it is manifest that while the lock is shown applied to a right hand door, it may be applied reversibly or to a left hand door by the mere duplication of the notches on both edges of the bolt and making the keeper extension 35 along both the top and bottom of the door piece. The latch 34' may thus be employed to operate by gravity or otherwise when applied from either side of the door piece or will co-operate with either set of notches in the bolt.

I claim:

1. In a combined door lock and stay, the combination of a rigid member for the door, a rigid member for the jamb, a bolt carried by and having constant engagement with the door member, and interengaging connection means between the bolt and the jamb member to provide a lock for the door when shut and serving also as a limiting stay for the door when ajar.

2. In a combined door lock and stay, the combination with a jamb piece and a door piece, of a member carried constantly by and having movable co-operation with the door piece, interengaging means between

- the movable member and the jamb piece, and means to move the movable member to constitute the same a limiting stop when the door is ajar and to serve as a locking bolt 5 when the door is shut.
3. In locking mechanism as set forth, the combination with a fixed jamb piece having a rigid pin and a relatively movable door piece, of a bolt carried by the door piece 10 and having sliding and swinging connection therewith, said bolt having formed at its outer end a hook the point of which is directed inward toward the door for locking engagement around said pin.
4. In lock mechanisms, the combination of two relatively movable bracket members one of which includes a rigid pin, a rigid bolt carried by the other bracket member and having a hook at one end for engagement 15 around said pin for making a jimmy-proof lock and to constitute a hinge around which the remote part of the bolt will swing when moved away from the bracket member which carries it to serve as a stay.
5. A lock as set forth comprising a fixed jamb piece having a rigid pin, a bracket to be carried by a swinging member with respect to the jamb piece and including a retainer which moves into proximity with the 20 jamb piece pin, and a bolt having sliding and swinging engagement through said retainer and having a hook at its outer end engageable over said pin when the swinging member approaches its closed position.
6. Mechanism as set forth in claim 5 in which the hook is so constructed that its point passes to the rear of the pin and is movable toward the swinging member for interlocking the hook end of the bolt around 25 the pin.
7. Mechanism as set forth in claim 5 in which the end of the bolt remote from the hook is arranged to swing outward at an angle to the normal position thereof in connection with the member which carries it.
8. The herein described combined door lock and stay comprising a fixed jamb piece having a rigid pin, a rigid door piece carried by the door, a combined sliding and 30 swinging bolt having a hook on its outer end for engagement around said jamb piece pin, and means serving to retain the bolt in constant but movable connection with the door piece.
9. Mechanism as set forth in claim 6 in which the bolt is slidable parallel with the door for locking or unlocking its hooked end with respect to the jamb piece pin and is swingable at an angle to the door for use as 35 a stay while pivoted around said pin.
10. Mechanism as set forth in claim 6 in which means is provided for retaining the bolt in parallel relation to the door piece for sliding movement into or out of locked position, and means co-operating with the bolt 40 to hold it from sliding out of locked position.
11. Mechanism as set forth in claim 8 in which means is provided to retain the bolt in close parallelism with the door piece and means is provided co-operating with the bolt to lock it in a plurality of positions of adjustment lengthwise along the door piece. 45
12. The herein described combined door lock and stay comprising a jamb piece having a fixed vertical pin, a door piece, a bolt carried by the door piece and slidably horizontally and parallel to the door piece and having at its free end a hook engageable 50 around said pin into locked position when the point of the hook and bolt are moved toward the door, and means to retain the bolt in constant engagement with the door piece, said retaining means providing for the swinging of the bolt away from the door 55 piece and around the pin as an axis.
13. Mechanism as set forth in claim 12 in which the retaining means includes a horizontal arm and the bolt is notched to receive said arm for making a positive interlock to limit the open swinging of the door. 60
14. In locking mechanism as set forth, the combination with a fixed jamb piece having a rigid pin and a relatively movable door piece, of a bolt carried by the door piece 65 and having constant connection therewith, said bolt co-operating with the door jamb to form a rotatable connection therewith which is non-detachable when the door is open but which may be disconnected when the door is closed. 70
15. In a combined door lock and stay, the combination of a rigid member for the door, a rigid member for the jamb, a bolt carried by and having constant engagement 75 with the door member, and interlocking connection means between the bolt and the jamb member to provide a jimmy-proof lock for the door when shut and serving also as a limiting stay for the door when ajar. 80
16. In a combined door lock and stay, the combination with a jamb piece and a door piece, of a member carried by and having movable co-operation with the door piece, interlocking means between the movable member and the jamb piece, and means to move the movable member to constitute the same a limiting stay when the door is ajar and to serve as a jimmy-proof lock 85 when the door is shut. 90
17. In a combined door lock and stay, the combination with a jamb piece and a door piece, of a member carried by and having constant connection with the door piece remote from the outside of the door, and key 95 means operative from the outside of the door to cause the member to move relatively to the door piece for engagement with the jamb piece to lock the door shut, said member remote from the jamb piece being moved 100

able away from the door while so engaged with the jamb piece to constitute it as a stay.

18. In a fastener for a door, the combination of a jamb piece, a casing for the door, a bolt having constant connection with the casing and movable along the same for making hinged locking connection at its outer end with the jamb piece, the end of the bolt

remote from the jamb piece being movable 10 angularly away from the door to constitute the bolt as a stay when the door is ajar, and keeper means for holding said remote end of the bolt adjacent to the door when shut while the bolt serves as a lock. 15

In testimony whereof I affix my signature.

EDGAR W. POHLIG.
